BOOTJACK

Filed May 4, 1929

Inventor

CHARLES KOSCH.

By *Clarence A. O'Brien*
Attorney

UNITED STATES PATENT OFFICE

CHARLES KOSCH, OF LYNBROOK, NEW YORK

BOOTJACK

Application filed May 4, 1929. Serial No. 360,493.

This invention relates to new and useful improvements in boot jacks, and aims to provide a simple and inexpensive device constructed for association with an ordinary chair, whereby to facilitate the removal of boots.

An important object of this invention is to provide a device of this character that may be manufactured and marketed at low cost, and that may be rigidly secured with any conventional type of chair, and that is so constructed as to facilitate the ready removal of boots, and this without regard to the tightness of the fit thereof upon the foot.

15 In the drawing wherein like reference characters indicate corresponding parts throughout the several views:—

Figure 1 is a horizontal section through the two rear legs of any conventional chair 20 with which my improved boot jack is shown as associated, the jack being disclosed mainly in top plan view, and partially in cross section.

Figure 2 is a fragmentary side elevation 25 of a chair leg, between two adjacent ones of which my improved boot jack is arranged, the said jack being illustrated in edge elevation.

Figure 3 is an enlarged transverse section 30 through the heel engaging portion of the boot jack, and taken substantially upon the line 3—3 of Figure 1, and

Figure 4 is a side elevation of a conventional chair equipped with my improved boot 35 jack, this view illustrating the manner of use of the device.

Now having particular reference to the drawing, my novel boot jack consists of a bar 5 of suitable metal constructed at its 40 opposite ends with chair leg engaging brackets 6—6. The length of the bar 5 is such as is also said brackets as to permit the same to be arranged over the rear legs of any conventional type of chair A. The open ends 45 of these brackets 6—6 are equipped with elongated thumb screws 7—7, that serve to close the open ends of the brackets, after the bar has been applied to the chair legs, as clearly illustrated in Figure 1.

50 Furthermore, one leg of each bracket 6 is

equipped with a thumb screw 8, whereby the bracket may be rigidly secured to the respective chair legs to prevent movement of the bar with respect thereto.

Intermediate its ends, said bar 5 is formed 55 with an outwardly extending relatively U-shaped heel receiving member 9, the inner surface of which is provided with a heel gripping edge 11, so as to prevent the heel of the boot from slipping upwardly through the member when the leg is drawn upwardly in the act of removing the boot from the foot, as generally suggested in Figure 4.

Rigidly secured to the bar 5 and in alignment with the heel receiving member 9 is an 60 inwardly extending somewhat elongated and U-shaped boot sole supporting member 10, upon which the sole of the boot is adapted to be placed after the heel thereof has been arranged through the heel member 9, also 65 as illustrated in Figure 4.

The brackets 6—6 are slightly out of parallel alignment with the longitudinal axis of the heel and sole members 9 and 10, so that when the boot jack is associated with the 70 chair, as illustrated in Figure 4, said sole and heel member will be on a slight inclination to properly support the foot.

75 In view of the foregoing description when considered in conjunction with the accompanying drawing, it will be apparent that I have provided a novel, simple, inexpensive and useful boot jack, that is well adapted for all of the purposes heretofore designated, and even though I have herein shown and described the invention as consisting of certain detailed structural elements, it is nevertheless to be understood that some changes may be made therein, without affecting the spirit and scope of the appended claims.

Having thus described my invention, what I claim as new, and desire to secure by Letters-Patent, is:

1. In a boot jack of the character described, a bar member having means at its opposite ends to facilitate its rigid association with a pair of adjacent legs of a chair, table or the like, a relatively U-shaped heel receiving member formed intermediate the ends of the bar, and a boot sole supporting member rig- 95 100

idly associated with the bar member in longitudinal alinement with the heel receiving member.

2. In a boot jack of the character described, a bar member, chair leg engaging brackets associated with the opposite ends of the bar, means carried by said brackets to facilitate their rigid engagement with the chair legs, a heel receiving member formed intermediate the ends of the bar member, and a boot sole supporting member rigidly associated with the bar member in longitudinal alinement with the heel receiving member.

3. In a boot jack of the character described, a bar member, chair leg engaging brackets associated with the opposite ends of the bar, means carried by said brackets to facilitate their rigid engagement with the chair legs, a heel receiving member formed intermediate the ends of the bar member, and a boot sole supporting member rigidly associated with the bar member in longitudinal alinement with the heel receiving member, the inner surface of said heel receiving member being bevelled at its top side to provide a boot heel gripping edge.

In testimony whereof I affix my signature
CHARLES KOSCH.
